Primary Examiner—Terry A. Wallace*Assistant Examiner*—Richelle Shelton*Attorney, Agent, or Firm*—Basil Travis[57] **CLAIM**

The ornamental design for an installation tool for drip irrigation systems, as shown and described.

DESCRIPTION

FIG. 1 is a perspective view of an installation tool for drip irrigation systems as shown from the bottom, front and one end;

FIG. 2 is an end elevational view of that shown in FIG. 1;

FIG. 3 is an elevational view of the opposite end;

FIG. 4 is a bottom plan view;

FIG. 5 is a top plan view;

FIG. 6 is a front elevational view;

FIG. 7 is a rear elevational view; and,

FIG. 8 is a front perspective view, the broken lines illustrating human hands, plastic pipe and holder are for illustrative purposes only and form no part of the claimed design.

FIG. 1

FIG. 2

FIG. 3

FIG. 4

FIG. 5

FIG. 6

FIG. 7

FIG. 8
